UNITED STATES PATENT OFFICE.

DAVID LINDSAY, OF OCEAN GROVE, NEW JERSEY.

FEATHERING PADDLE-WHEEL OR PROPELLER.

1,246,289.

Specification of Letters Patent. Patented Nov. 13, 1917.

Application filed August 16, 1915. Serial No. 45,625.

To all whom it may concern:

Be it known that I, DAVID LINDSAY, a citizen of the United States, residing at Ocean Grove, in the county of Monmouth and State of New Jersey, have invented certain new and useful Improvements in Feathering Paddle-Wheels or Propellers; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention has reference, generally, to an improved construction of feathering paddle-wheel or propeller for marine propulsion; and the invention has for its principal object to provide a simple, compact and strong construction of paddle-wheel or propeller known as "feathering-wheels" wherein each blade or paddle is made to present its face transverse to the line of motion during some certain part of its revolution, or while such position would assist in propulsion, and during the balance of its revolution the face of the blade or paddle is turned so as to be in the plane of its rotary movement, and thus offer a minimum of resistance. The paddle-wheel or propeller thus operating is intended to be rotated under water, in other words while submerged.

A further object of the present invention is to provide such a feathering paddle-wheel or propeller with means for controlling the feathering operation so that the same may be caused to take place at any point or period of its revolution, whereby the paddle-wheel or propeller may be used to steer the boat to which it is attached in either direction, and also to propel the boat sternward without reversing the operating of the driving mechanism of the paddle-wheel or propeller.

Another object of the present invention is to provide a feathering control means, as above indicated, which can be operated while the paddle-wheel or propeller is in motion without necessity of stopping or otherwise interfering with its driving mechanism.

Other objects of the present invention, not at this time more particularly enumerated, will be clearly understood from the follow-

ing detailed description of my present invention.

With the various objects of my present invention in view, the same consists, primarily, in the novel construction of submerged feathering paddle-wheel or propeller hereinafter set forth; and the invention consists, furthermore, in the novel arrangements and combinations of the several devices and parts, as well as in the details of the construction of the same, all of which will be more fully described in detail in the following specification, and then finally embodied in the claims which are appended to and which form an essential part of said specification.

The invention is clearly illustrated in the accompanying drawings, in which:

Figure 1 is a longitudinal vertical section of the submerged feathering paddle-wheel or propeller made according to and embodying the principles of my present invention.

Fig. 2 is a horizontal section of the same drawn on an enlarged scale, and taken on line 2-2 in said Fig. 1 looking downward, one of the paddles or blades being shown in section and the rest in elevation.

Fig. 3 is a diagrammatic representation of the feathering operation of a paddle or blade during its revolution, said view showing the propelling position, the position during the act of feathering, and the final completed position after feathering.

Fig. 4 is a detail section taken on line 4-4 in said Fig. 2, illustrating a pivot bearing in the carrying-ring located at the outer ends of the paddles or blades.

Fig. 5 is an inner end view of a paddle or blade detached from the wheel or propeller.

Similar characters of reference are employed in all of the hereinabove described views, to indicate corresponding parts.

Referring now to the said drawings the reference character 1 indicates the complete feathering paddle-wheel or propeller made according to and embodying the principles of my present invention, the same comprising a housing formed in two sections consisting of an upper housing section 2 and a lower housing section 3, the same being separated horizontally, and normally secured together by bolts 4. The said housing sections 2 and 3, when normally secured together, provide an interior chamber 5, the purpose of which will be subsequently set forth. Ex- 110

tending upwardly from said upper housing section 2 is a hollow shaft or sleeve 6, preferably forming an integral part of said upper housing-section 2. The annular marginal meeting surfaces of the connected housing sections are provided with a plurality of radiating openings which provide radiating bearing-portions 7, corresponding to the position and number of paddles or 10 blades employed.

Each paddle consists of a blade 8 of any desired shape, preferably in a form widening outwardly toward its outer end. Each blade 8 is provided at its outer end with 15 a journal-stud 9, having a rearwardly extending bifurcated fastening plate 10 adapted to straddle the thickness of the blade, and rivets 11 passing through said fastening plate 10 firmly affixes said journal-stud 9 20 to the blade.

The reference character 12 indicates an outer supporting ring having enlarged portions 13 in which are formed sockets providing bearing-portions 14 in which said 25 journal-studs 9 are mounted. Said ring 12 extends around the outer ends of the blades 8, and not only serves to pivot the said outer ends but also to strengthen the blades and maintain the same properly spaced one from 30 another. Said supporting ring 12 rotates with the paddle-wheel or propeller, and is made of a tapering thickness out to its outer periphery so as to offer as little resistance to the water as possible.

35 Secured to the inner end of each blade 8 is a stud-shaft or journal-member 15, the same being provided at its one end with a bifurcated fastening plate 16 which straddles the thickness of the blade, and rivets 17 40 passing therethrough firmly affixes said stud-shaft or journal-member to the blade.

Said stud-shafts or journal-members 15 are rotatably mounted in the bearing-portions 7 formed in said housing sections 2 45 and 3, so that their free ends extend into said interior chamber 5 provided by the latter. Integrally formed at the free end of each stud-shaft or journal-member 15 is a crank-arm 18 having a crank-pin 18' projecting therefrom. Mounted upon each 50 crank-pin 18', if desired, is an antifriction roller 19.

The paddle-wheel or propeller is designed to be mounted beneath the boat-bottom 20, 55 at the stern thereof, and is arranged in a horizontal position. There are, of course, many ways of mounting said paddle-wheel or propeller relative to the boat to be propelled thereby, consequently the means for 60 mounting the same, such as shown in the drawings, must be deemed merely illustrative and not in a limiting sense. Such means comprises a suitable bearing member 21 affixed to the boat-bottom 20, and provided 65 with any suitable form of stuffing-box 22

adapted to render the same water-tight. Rotatably mounted in said bearing-member 21, and extending upwardly therethrough into the interior of the boat is the hollow shaft or sleeve 6, to the upper end of which is 70 secured a bevel-gear 23, with which meshes a bevel pinion 24 through which the power of the transmission shaft 25 is applied to rotate said hollow-shaft or sleeve 6, and consequently the housing-sections 2 and 3 75 and the blades 8 connected therewith.

Mounted within the interior chamber 5 of said housing sections 2 and 3 is a cam-member 26 which is provided in its sides with a cam-groove 27, which for convenience in explaining the operations effected thereby, I will describe as possessing an upper groove portion and a lower groove portion. 80

The crank-pins 18', with their anti-friction rollers 19, enter said cam-groove 27 and ride therein.

Secured to said cam-member 26 is an upwardly extending vertical-shaft 28, which extends through said hollow-shaft or sleeve 6, and which is preferably journaled in a stationary sleeve 29. The lower or under side of said cam-member 26 is provided with a pivot journal 30 which is supported upon a removable foot-step bearing 31 secured in 90 said lower housing-section 3. Said vertical-shaft 28 may be rotated to turn said cam-member 26 to shift its position for the purpose of shifting the point of the feathering of the blades 8, as will be subsequently described. In order to secure the cam-member 26 in any position to which it has been shifted or adjusted by rotating the vertical shaft 28, I provide a stationary notched quadrant 32, and I secure upon said vertical-shaft 28 an articulated lever-arm 33 which 95 co-operates with said notched quadrant. Of course, it will be understood that said quadrant and lever-arm may be separated from said vertical-shaft 28, and interconnected, 100 therewith by intermediate transmission mechanism if desired, or any other desirable means for imparting the necessary rotary movement to said vertical-shaft 28 may be employed. 105

110 It will be apparent that the cam-member 26 is supported independently of the housing-sections and said hollow-shaft or sleeve 6 by means of which the paddle-wheel or propeller is revolved. Thus while the housing-sections and blades 8 connected therewith are revolved by the driving mechanism, the cam-member 26 remains stationary, but may be independently moved for adjustment purposes. 115

The cam-groove 27 is formed so as to give the crank-pins 18' a vertically reciprocating movement as they travel around the cam-groove, and this reciprocating movement oscillates the crank-arms 18 sufficiently to give 120 125 130

the blades 8 a rotation on their axes to the extent of a quarter turn, thus moving the blades 8, alternately to vertical and horizontal positions. The cam-groove is so shaped, 5 by preference, that two or more blades 8, at least, may at all times operate to propel the boat.

An inspection of Fig. 3 of the drawings will explain the action of the cam-groove 10 27 upon the crank-pins 18', crank-arms 18 and blades 8. When the crank-pins are moving in the lower groove-portion of the cam-groove the blades 8 are presented face- 15 ward to the water and in propelling position. As the crank-pins enter the rise from the lower groove-portion to the upper groove-portion, the crank-arms are caused to move upward, thus turning the stud- 20 shafts or journal members 15, and when the upper groove-portion is reached the stud- shafts or journal-members have completed a quarter turn and consequently the blades 8 are presented edgewise to the water, or in feathering position relative thereto. As the 25 rotation of the paddle-wheel and its blades continue, the crank-pins 18' continue their travel until they reach the descent joining the upper groove-portion to the lower, and are thereby caused to move downward again, 30 thus turning the stud-shafts or journal members a quarter turn in the opposite direction, thereby the blades 8 are again turned to propelling position, this reciprocating oscillation of the blades continuing as the 35 crank-pins are carried around in contact with the stationary cam-groove 27 by the revolution of the paddle-wheel or propeller.

While the cam-member 26 remains in any given position, the blades will be made to 40 work—that is will be changed from vertical to horizontal positions—at a certain part of their revolution corresponding to the cam rise and descent in the cam-groove 27. If the vertical shaft be turned so as to turn the 45 cam-member 26, thus changing the positions of the cam rise and descent of the cam-groove, the working point of the blades will be correspondingly changed. It will thus be apparent that by shifting or adjusting the 50 cam-member 26, the pilot may operate the paddle-wheel or propeller in such a way as to shift its propelling force so as to steer or change the course of the boat as desired.

I am aware that some changes may be 55 made in the arrangements and combina-

tions of the various devices and parts, as well as in the details of the construction of the same, without departing from the scope of the present invention as set forth in the foregoing specification and as illustrated in 60 the accompanying drawings. Hence, I do not limit my invention to the exact arrangements and combinations of the parts as above described and as illustrated in the accompanying drawings, nor do I confine myself 65 to the exact details of the construction of the said parts.

I claim:

In a device of the kind described, a rotary housing providing an interior chamber, a 70 hollow shaft extending upwardly from said housing for rotating the same, a stationary tubular sleeve upon which said hollow shaft rotates, said housing being provided at its outer marginal portions with radiating bearing-portions extending to said interior chamber, a plurality of paddleblades, journal-members affixed to the inner ends of said blades and journaled in said bearing-portions of said housing, a cam-member having 75 a cam-groove positioned in said interior chamber and normally stationary relative to said housing, crank-arms connected with the inner ends of said journal-members, crank-pins projecting from said crank- 80 arms into said cam-groove and traveling therein when said housing and said blades are revolved, an outer ring having bearing openings therein, journal studs connected with the outer ends of said blades 85 and journaled in said bearing openings of said ring, means for independently adjusting said cam-member to shift the feathering point of said blades, comprising a vertical shaft 90 affixed to said cam-member and extending 95 upwardly through said stationary tubular sleeve, means for rotating said shaft as desired, and means coöperating with said vertical shaft for holding the same against rotation and thus locking said cam-member in 100 desired adjusted position, all for the purposes described.

In testimony, that I claim the invention set forth above I have hereunto set my hand this twelfth day of August, 1915.

DAVID LINDSAY.
